FROG MAKING MACHINE

Nathan E. Branson, Oakland, Calif., assignor to
Edmond C. Matignon, Oakland, Calif.

Application February 20, 1948, Serial No. 9,759

6 Claims. (Cl. 140—71)

1

This invention relates to a machine for making frogs, such as used to support flowers in a vase.

The conventional frog comprises a flat base portion, usually of lead or a lead alloy, in which a plurality of pins are embedded and from which the pins project in a uniform pattern. The stems of flowers, for example, are impaled on the pins, thus being provided with support.

The machine of this invention comprises a pin making element, preferably of the type described and claimed in my copending application Serial No. 708,585, filed November 8, 1946, entitled "Pin-Forming Machine"; a pin setting or orienting element whose function it is to set or orient the pins in a predetermined pattern corresponding to the pattern desired in the final product; and a molding element whose function it is to mold the base to produce the final product. While these several elements co-act to produce a unitary result, as will be apparent, and provide a machine which greatly accelerates the production of frogs and produces frogs of uniformly high quality, the several elements are also useful, as will be apparent, for other unit operations.

In the production of frogs as heretofore carried out, the operation of setting the pins in a predetermined pattern corresponding to the pattern of the end product has been laborious and time consuming. Thus, in one such method, pins having pointed tips and bifurcated or fish tail heads are made in the manner and with the machine described in my aforesaid copending application, and the pins so made are subjected, separately from the pin-making operation, to agitation to thread them through openings in a perforated die, in accordance with the predetermined pattern.

It is an object of the present invention to provide a mode of operation and a machine whereby pins or other like objects, which are to be set in a predetermined pattern, can be set or oriented rapidly and accurately.

It is a further object of the invention to provide a machine capable of receiving headed pins as made and expelled intermittently but rapidly from a pin cutting machine, such as that of my above-mentioned copending application, and accurately setting the pins, in synchronism with the pin cutting machine, in a predetermined pattern.

It is a still further object of the invention to provide a unitary structure or machine, embodying both a rapidly, intermittently operable pin cutting element and a pin setting element synchronized with the cutting element and adapted to set the pins in a suitable die in ac-

2

cordance with a predetermined pattern, the two said elements being operable from a common drive shaft.

It is a particular object of the invention to provide a pin setting machine which is operable to receive pins one by one at a fixed point and is mechanically operable to shift a perforated, pin-receiving die from point to point so as to present, in sequence, each perforation of the pin-receiving die to the said fixed point so as to receive a pin and to completely load the die with pins.

It is a further particular object of the invention to provide a device for receiving a plurality of sets of headed pins, each arranged in a predetermined pattern, and to mold a base about the headed portions of the pins.

It is a still further particular object of the invention to provide a unitary machine capable of receiving wire from a spool or coil, rapidly cutting the wire into headed pins, feeding the pins to and setting them in a receiving member in a predetermined pattern, and molding a base about the headed ends of the pins to produce a frog or the like.

25 These and other objects of the invention will be apparent from the ensuing description and the appended claims.

The invention will be better understood by reference to the accompanying drawings, in which:

30 Fig. 1 is a fragmentary view in front elevation of the machine of the invention in its preferred embodiment, the omitted portion of the view omitting merely duplicate elements of the machine.

35 Fig. 2 is a top plan view of the same.

Fig. 3 is a section taken along the line 3—3 of Fig. 1, showing in plan view the pin receiving dies, part of the cam element and the molding element.

40 Fig. 4 is a transverse section taken along the line 4—4 of Fig. 2, showing the pin cutting element, the pin orienting element and the molding element.

45 Fig. 5 is an enlarged, fragmentary view, partly in front elevation and partly in section, showing the construction of the pin cutting and pin orienting elements.

50 Fig. 6 is a transverse section taken along the line 6—6 of Fig. 2, showing the Geneva movement used to actuate part of the pin orienting element and also showing a part of the pneumatic pin ejector.

55 Fig. 7 is an enlarged, fragmentary section taken along the line 7—7 of Fig. 6, showing a part of

the air passage employed in the pneumatic pin ejector.

Fig. 8 is an enlarged fragmentary view in perspective and on an exaggerated scale, of the orienting cams from which the pin orienting movement is derived, showing also a diagrammatic view of a pin receiving die.

Fig. 9 is an enlarged fragmentary view of the pawl and ratchet mechanism employed to actuate the orienting cams.

Fig. 10 is a section taken along the line 10—10 of Fig. 9.

Fig. 11 is a section taken along the line 11—11 of Fig. 10.

Fig. 12 is a section taken along the line 12—12 of Fig. 5, showing certain details of construction of the pin orienting element.

Fig. 13 is a view in front elevation of the molding element, showing one of the pouring vessels in section.

Fig. 14 is a section taken along the line 14—14 of Fig. 3, showing certain details of the molding element.

Fig. 15 is a fragmentary detail in transverse section of the molding element, showing the means of transferring pins thereto.

Fig. 16 is a somewhat similar view of the molding element, showing the manner of removing a molded frog.

Fig. 17 is a fragmentary top plan view of the molding element, showing the covers removed and the pin orienting dies in place.

Fig. 18 is a fragmentary, longitudinal section through the molding element showing certain details of construction.

Referring now to the drawings, and more particularly to Figs. 1 and 2, the machine is supported upon a table 1 having legs 2 and a top portion 3. Power is provided by a motor 4 bolted to the table and provided with a solenoid brake 5 adapted to quickly bring the mechanically driven elements to rest when a cycle of operations has been completed. Power is transmitted from the motor to the machine through pulleys 6 and 7, a belt 8 trained about the pulleys, a gear reducing box 9 and a drive shaft 11 carried at one end in the gear box 9 and at its opposite end in a bearing 11a formed in upright brackets 25 and 26. A conventional push button switch and relay (not shown) may be provided for starting the motor 4.

The main elements of the machine, in the order described hereinafter, are a battery of pin cutting elements 15, an equal number of pin orienting elements 16, a cam element 17 for actuating the pin orienting elements and a molding or casting element 18 for molding bases on the oriented pins.

The pin cutting elements

Referring now more particularly to Figs. 2, 4 and 5, a main framework is provided by end brackets 25 and 26 and a longitudinal bracket 26a bolted thereto. The pin cutting elements 15 are supported upon the framework by means of keys 27 engaging keyways 28 and by bolts 29. The housing of each cutting element 15 is formed by side walls 30 and 31, rear wall 32 and front wall 33. Within each housing are disposed two rotary cutting blades 37 and 38 keyed to parallel shafts 39 and 40, respectively. The shafts 39 and 40 are carried in bearings formed in the side walls 30 and 31 of the housing, one such set of bearings being shown at 41 and 42 in Fig. 5. Power for driving the cutting blades 37 and 38 is provided

by a gear 43 keyed to the drive shaft 11, meshing with a gear 44 which is keyed to a hub 45 by a shear pin 46. The hub 45 is keyed to the shaft 39, as shown. A gear 50, keyed to the shaft 39 on the opposite side of the blade 37, meshes with a similar gear not shown keyed to the shaft 40, thus providing an equal and opposite drive for the blade 38.

The rotary cutting blades 37 and 38 are similar in design and function to the rotary blades described in my above-mentioned copending application Serial No. 708,585. That is, each of the blades 37, 38 is provided with a peripheral groove 52 having a narrow segment to grip the wire and pull therebetween a predetermined length of wire, and each blade is also provided with a cutting member 53 located in a stepped bore 54 and adjustable therein by means of a set screw 55. Each cutting member 53 is provided with a V-shaped cutting tip 56. The tips 56 cut the wire to produce pins of predetermined length, each having a pointed tip and a bifurcated or fish tail head. As also described in my copending application, each cutting element is provided with a wire feeding means 60, comprising a tube 61, a collar 62 bolted to the housing, a chuck 63 to center the wire 64, a spring 65 to exert tension on the chuck, and a nut 66 engaging a pin 67 on the chuck when it is desired to thread a new piece of wire through the tube 61.

The pin cutting element thus described differs from that described in my copending application mainly in the shape of rotary blades 37 and 38 which, instead of being circular in cross-section, are extended outwardly at 68, as shown, to provide clearance for the star wheel 75, which is described in detail hereinafter.

In operation, the cutting element 15 functions in the same manner as described in my copending application. A supply of wire 64 is threaded through the tube 61 and between the blades 37 and 38. The latter rotate continuously, and during each revolution they grip the wire, pull through a predetermined length thereof, and then cut the wire to form a pin 70 having a pointed tip and a fish tail head.

The pin orienting element

The pin orienting element comprises a plurality of star wheels 75 and dies 76, equal in number to the cutting elements 15. Each star wheel 75 is secured at one end of a shaft 77 which is rotatable in a bearing 78 formed in a block 79, which depends from and is secured to the housing of the adjacent cutting element. Secured to the opposite end of the shaft 77 is a driven wheel 80. Rotation of each star wheel 75 is derived by means of a Geneva movement, comprising the driven wheel 80 and a driving wheel 85 secured to the shaft 40. The driving wheel 85 is provided with an inwardly projecting pin 86, which engages radial slots 87 of the driven wheel 80. The driving wheel 85, as shown more clearly in Fig. 6, is also provided with a concentric locking surface 88 projecting inwardly therefrom, which engages an arced segment 89 of the driven wheel 80 to lock the same in fixed position between the incremental movements thereof.

Each star wheel 75 is provided with radial passages 95 to receive the pins 70 from the cutting element 15. A pin retaining member 96 depending from the housing of the cutting element abuts against the star wheel to retain the pins in their respective passages 95 until a

passage has rotated through 180° to the inverted position shown at 97 and is ready for ejection into the die 76.

The timing of the intermittent angular movement of the star wheel 75 is such that it advances 45° for each revolution of the cutting blades 37 and 38. Thus, it will be seen that each time a radial passage 95 is brought to pin receiving position, the diametrically opposite passage is brought to pin ejecting position at 97.

Positive means for ejecting the pins 70 from the passages 95 is provided by compressed air from a manifold 105 bolted to the bracket 26a. As shown more clearly in Fig. 6, the manifold 105 communicates with an outwardly opening valve 106 associated with each cutting element 15. The stem of each valve 106 bears against a cap 107 which is slidable over the valve body 108. The periphery 109 of driving wheel 85 acts as a cam, having a high point 110 which engages the cap 107 at the moment a radial passage 95 of the star wheel 75 is brought to pin ejecting position. Air is thus admitted through the valve 106 and passes, first through a V-shaped duct 111, thence through a duct 115 and a duct 116 formed in the block 79. The latter duct widens into a cylinder 117 containing a piston 118, which is forced by the air pressure against the star wheel 75, thus effectively sealing the end of the air passage and permitting escape of air only through the bore 119 in the piston to the radial passage 95, thus causing positive ejection of the pin. The plug and opening shown at 120 in Fig. 7 are merely for convenience in drilling and sealing the V-duct 119.

The dies 76 are each in the form of a block having vertical perforations 125 of a diameter such as to receive the pins 70 and to support them in vertical position but to allow the pins to slide through except when prevented by a bottom closure. These perforations are arranged in accordance with the desired pattern of pins in the final product. The dies 76 are carried in a rectangular framework 126 comprising longitudinal bars 127 and end bars 128. The end bars 128 are provided with keys 129 slidable in keyways 130 formed in brackets 122. A bottom closure for the dies 76 is provided by means of a plate 131 slidible in grooves 132 formed in the longitudinal bars 127. The plate 131 is provided with openings 133 for a purpose hereinafter described, and it is urged to the right, with the solid portions abutting the dies 76 to serve as a bottom closure therefor, by means of a spring 134 secured to the plate 131 at one end by a bracket 135 which rides in a slot 136, and at its opposite end to the framework at 140. Finger holds are provided at 141 as a means of pushing the closure to the left to open position.

Locking arms 142 pivoted at 143 are also provided, and in the angular position shown in Fig. 3, these arms lock the framework 126 and dies 76 in the inward or pin-receiving position, but upon turning the arms inwardly against the action of the springs 144, the framework is unlatched and can be pulled outwardly to transfer the pins to the molding element as described hereinafter.

The pin orienting element 16 also comprises a structure generally designated as 145, which provides support for the framework 126 and the dies 76 and which imparts longitudinal and transverse movement thereto. The structure 145 is better understood and is described hereinafter with reference to the cam element 17.

The cam element

The orienting movement of the dies 76 is derived from the cam element 17. As shown in Fig. 1, this element comprises a ratchet wheel 150 and upper and lower cams 151 and 152, all of which are keyed to a common shaft 153 and reinforced by pins 154. As shown in Figs. 1 and 10, a bevel gear 155 keyed to the drive shaft meshes with a bevel gear 156 having a hub 157 rotatably mounted on a fixed shaft 158. An eccentric insert 159 keyed to the hub 157 by a shear pin 160 is provided, and a pawl 165 is rotatably mounted on the insert 159 to allow pivotal movement of the pawl thereon.

15 As will be seen by reference to Figs. 9 and 10, rotation of the hub 157 and of the eccentric insert 159 will impart to the pawl 165 a reciprocating motion and will impart to the ratchet 150 an intermittent angular motion as the pawl successively engages the teeth 166 of the ratchet. As shown in Figs. 1 and 2, the ratchet 150 is provided with a stop button 167, and adjacent the ratchet is a switch box 168 containing a suitable switch element (not shown) and having an arm 169 provided with a roller 170. When the ratchet 150, hence also the cams 151 and 152, have completed one revolution, the roller 170 engages the button 167, thus raising the arm 169 resulting in opening the switch in box 168. The switch is connected by suitable leads (not shown) with the motor circuit and with the solenoid circuit, thus bringing the motor to an immediate stop when a single revolution of the ratchet 150 has been completed.

35 A holding pawl 175 is also provided, this pawl being rotatably mounted on the fixed shaft 158 and being provided with a pin 176 adapted to nest between adjacent teeth of ratchet 150 and to hold the same in fixed position between the feed strokes of the driving pawl 165. Leaf springs 177 and 178 secured to a bracket 179 hold the driving pawl 165 and the holding pawl 175, respectively, firmly in engagement with the teeth of ratchet 150.

45 The resulting intermittent, angular movement of the cams 151 and 152 is imparted to the dies 76 through the structure 145 above mentioned and upper and lower cam followers 180 and 181. The upper follower 180 is provided with rollers 50 182 at each end, as shown, and the followers are slidable through a block 183.

The structure 145 comprises, and is largely enclosed by a box-like base 190 formed from end pieces 191, side pieces 192, a cover portion 193 and a bottom portion 194, the latter being provided with openings 195. The base 190 is supported by rods 196 passing through both end pieces 192 and anchored in the end brackets 25 and 26. The base 190 is also slidable along the rods 196, longitudinally of the machine.

65 Longitudinal movement of the base 190, hence of the framework 126 and the dies 76, is derived from the lower cam 152 by its action upon the lower follower 181, which bears against a block 198 secured to the adjacent end of the base 190. This force slides the base 190, and with it the framework 126 and dies 76, longitudinally of the machine along the rods 196. A shaft 199 is provided at the opposite end of the base, which is complementary to the follower 181. This shaft passes through a block 200 and is urged to the right by an arm 205 pivoted at 206 and loaded by a spring 207 so as to positively urge the base 70 190 and the follower 181 to the right and to main-

tain the latter firmly in engagement with the lower cam 152.

Transverse movement of the framework 126 and dies 76 is provided as follows: Referring more particularly to Figs. 5 and 12, the cover portion 193 is slidable over end and side pieces 191 and 192 of the base 190. Depending from and secured to the cover 193, at each end thereof, are two parallel, spaced plates 208, each having a transverse bore 209 to receive a slide rod 10 210 which runs transversely of the base 190 and is anchored in the side pieces 192 thereof. Secured to the bottom of each plate 208 are trackways 211, and a plate 215 which is slidable through a slot 216 formed in the adjacent end 15 piece 191, is guided for longitudinal movement by the trackways 211. Each plate 215 is provided with a flange 217 at its outer end to increase the bearing surface, and the two plates 215 are connected or bridged by a strip of sheet metal 218. Secured to the underside of each plate 215 are two spaced bars 219 forming a keyway 220 which is disposed at a 45° angle with respect to the longitudinal axis of the machine. A key 221 secured to a block 222 which in turn 20 25 is bolted to the table 4, engages the keyway 220.

It is thus apparent that, when the upper cam 151 forces the upper follower 180 to the left, the key 221 engaging the diagonal keyway 220 imparts to the framework 126 a component 30 which is 45° from the longitudinal axis of the machine, while the slide rods 210 confine the movement of the framework to a direction perpendicular to the longitudinal axis of the machine.

As in the case of the lower cam follower 181, there is also provided on the opposite side of the base 190, a shaft 223 complementary to the upper cam follower 180 and having similar rollers 224. Similarly, a pivoted arm 225 loaded by a spring 40 45 226 bears against the shaft 223 to hold the upper cam follower 180 positively and firmly against the upper cam 151.

Referring now to Fig. 8 of the drawings, the points 230 of each cam form arcs of concentric circles 231 spaced a given distance apart, e. g., one-tenth of an inch. This spacing is the same as the spacing of the perforations 125 in the dies 76. The radial lines 232 are equiangularly spaced and they are equal in number to the perforations 125 in a single die 76 and to the number of teeth 166 in the ratchet 150.

Taking the perforation 233, whose index or rectangular co-ordinates are 1, 6, as the origin or starting point, a pattern is first worked out on the die 76 by trial and error, such that a pattern of movements is developed whereby each perforation in turn can be reached without omission or repetition. When this pattern of movements has been worked out, the pattern of the cams 151 and 152 is worked out with the aid of the indexing shown in Fig. 8. It has been found that such a pattern can be derived as will result in orienting each of the perforations in pin-receiving position by a succession of movements each of which, except one, is parallel to or is at 90° to the longitudinal axis of the machine, and each of which displaces the dies from a given pin-receiving position to an adjacent pin-receiving position. The one exception noted is a diagonal movement between diagonally adjacent positions. A pattern of movements for the pin setting die of a typical frog having a circular configuration of the pins centered one-tenth inch apart, is given in the table below, in which the one diagonal movement is underscored.

58	11	7	119	2	8
59	12	7	120	1	8
60	12	6	121	1	7
61	13	6			

In this table, "Pin No. 1" indicates the first pin inserted, being that pin whose index number is 1, 6. "Pin No. 2" is the second pin inserted, being that pin whose index number is 2, 6. Also, "Pin No. 1" and "Pin No. 2" correspond to the first and second cam movements, and the indices 1, 6 and 2, 6 correspond to the first two operative positions of the cams 151 and 152.

It is thus apparent that, as the drive shaft 11 rotates, thus actuating the pin cutting elements 15 and the star wheels 75 as described above, the cams 151 and 152 are also actuated in synchronism with the cutting elements and the star wheels; and it is also apparent that the cams will orient the dies 76 in a succession of pin-receiving positions so as to load each die with a full set of pins. When the last pin has been inserted in each die, the machine will be brought to an immediate stop as explained above, in readiness for the next cycle of operations. The framework 126 containing the loaded dies 76 is then removed from the pin orienting element in the manner described above and is transferred to the molding element 18 described hereinafter.

The molding element

The molding element 18 comprises a molding structure 250 and a pouring structure 251. The

latter comprises a manifold 252 communicating with a supply of molten lead or other molten metal from which the base of the frog is to be molded. The molten metal is constantly circulated through the manifold by suitable means (not shown). The manifold is provided with pouring outlets 254, and beneath each outlet 254 is a pouring and measuring vessel 255 carried in an outer sleeve 256 and sealed by inner sleeves 257. The pouring vessels 255 are carried by a broken shaft 258 carried in bearings 259 formed in brackets 260, and they can be rotated from filling to pouring position by a handle 265 at one end of the shaft. Each outer sleeve 256 is provided with inlet and outlet openings 266 and 267, respectively, and with a smaller breather opening 268, as shown in Fig. 4. Each pouring vessel 255 is provided with an opening 269 for filling and pouring and with a smaller, breather opening 270.

The molding structure 250 comprises a hinged cover member 271, a mold section 272 and a base 273. The entire structure is slidable transversely of the machine by means of keys 275 engaging keyways 276. The cover member 271, comprising lids 279 joined by bars 280, is hinged to rod 285 by ovate slots 286 formed on brackets 287. Each lid 279 is provided with an opening 288 for receiving molten metal. A spring 289 compressed against one of the brackets 287 urges cover member 271 to the right to align the lids 279 with the respective mold cavities 290, as shown.

The mold section 272 is provided with a plurality of mold cavities 290, equal in number with the dies 76 in the framework 126, and it is further provided with notched flanges 291 having diagonal cam surfaces 292. The base 273 is provided with perforations 293 to receive the pins 70, the pattern of the perforations 293 being the same as in the dies 76. Abutting the base 273 along each side thereof is a cam bar 294 having diagonal cam surfaces 295 complementary to the cam surfaces 292 of the flanges 291.

Two foot treadles 295 and 296 are provided to actuate the cam bar 294 and the cover member 271, respectively, in the manner and for the purposes set forth hereinafter. Springs 297 and 298 urge the treadles upwardly, and links 299 and 300 connect them to pivoted levers 301 and 302, as shown. Further details of construction comprise the slidable bottom closure 303, shown most clearly in Fig. 18, having openings 304 adapted to register with the openings 305 in the base 273.

In operation, when a set of dies 76 is loaded with pins as described above, the framework 126 is removed from the pin orienting element of the machine, and it is placed on top of the mold section 272. As shown most clearly in Fig. 17, the framework 126 is accurately aligned with respect to the mold cavities 290 by means of keys 129 formed on the end bars 128 engaging keyways 307 formed in the ends of the molding structure, and by means of spring loaded pins 308 engaging notches 309 formed in the end bars. With the framework 126 thus aligned, the bottom closure 131 is shifted to the left by pushing the finger holds 141 manually. The pins 70 drop from the dies 76 into the corresponding perforations 293 of the base 273, where they are held in vertical position and with their heads protruding into the mold cavities 290, by means of the bottom closure 303. The framework 126 and the dies 76 can be immediately returned to the pin orienting element for reloading with pins.

The pouring vessels 255, each of which always

contains a measured amount of molten metal, are then inverted to pouring position by means of the handle 265. A stream of molten metal falls from each vessel and through the openings 288 in the underlying lid 279, thus filling the respective mold cavity with the metal. While the cast metal is still soft, the sprues formed in the openings are sheared off by stepping on the foot treadle 296. This causes the lever 302 to engage the adjacent end of the cover member 271, pushing it to the left to shear off the soft metal at the upper level of the mold cavities. The molding structure is then pulled outwardly along the keyways 276, to the position shown in Fig. 15, so as to be clear of the manifold 252. The cover member 271 is then pivoted to the open position, as shown in Fig. 16 (which causes the sheared sprues to fall out), and the treadle 295 is depressed. This urges the cam bar 294 to the right, thus raising the mold section 272 to the position shown in Fig. 16. By this means the pins 70 of the frogs 310 are raised clear of the base 273, sufficiently that they can be lifted manually or by tongs without danger of bending the pins or damaging the base of the frog.

If for any reason, such as a defective pin or pins, it is desired to remove the pins 70 from the base 273 before casting the metal, such removal may be effected, as will be clear from Fig. 18, by sliding the bottom closure 303 to the right to align the openings 304 with the openings 305. The pins will then fall out of the bases 273.

It is thus apparent that a machine has been provided which is fast and dependable in operation; which accurately and neatly times a sequence of operations necessary for making frogs and the like, such that a single operator can attend a battery of units, each capable of cutting pins, orienting the pins and molding the final product; and which embodies numerous features rendering more efficient each of the unit operations.

While I have shown the preferred form of my invention, it is to be understood that various changes may be made in its construction by those skilled in the art without departing from the spirit of the invention as defined in the appended claims.

Having thus described my invention, what I claim and desire to obtain by Letters Patent is:

1. A machine for making frogs and the like comprising: a rotatable drive shaft; a pin cutting element comprising a pair of tangentially disposed, rotary pin cutting members adapted to receive a wire and to cut a pin of predetermined length during each revolution of said cutting members; means operatively connecting said drive shaft with said cutting members to rotate the latter continuously; a rotary pin transmitting element adapted to receive pins from said cutting members at a pin-receiving position and to eject the pins at a pin ejecting position; means operatively connecting said transmitting element with said drive shaft to impart intermittent angular movement thereto in synchronism with said cutting members to receive pins therefrom; a pin-receiving die provided with pin-receiving perforations defining a plurality of pin-receiving positions; a support for said die slidable along either of two intersecting lines; and means operatively connected with said drive shaft and operable to slide said die in increments along either of said lines from a first pin-receiving position in sequence to each of the remaining pin-

receiving positions in synchronism with the ejection of pins from said pin transmitting element.

2. A machine of the character described comprising a rotary pin cutter adapted to receive a continuous length of wire and to cut the same into pins, rotary pin feeding means for receiving each pin from said pin cutter and transferring it to a delivery station, pin setting means shiftable in two directions to move in a plane adjacent said pin delivery station and having pin retainers to receive and retain pins in a predetermined pattern, a common drive shaft, means operatively connecting said pin cutter with said common drive shaft, means operatively connecting said pin feeding means with said drive shaft, and means operatively connecting said pin setting means with said drive shaft, said connecting means being operable to rotate said pin cutter and pin feeding means and to shift said pin setting means in timed relationship to receive each pin from the pin cutter, to transfer each pin to said delivery station and to shift the pin setting means to align the pin retainers in sequence with the delivery station.

3. A machine of the character described comprising means for supplying pins one by one at a pin receiving station, rotary pin feeding means for receiving each pin at said station and transferring it by rotation to a pin delivery station, air jet means operable to eject each pin from the pin feeding means at said delivery station, shiftable pin setting means shiftable in two directions to move in a plane adjacent said pin delivery station and having pin retainers to receive and retain pins in a predetermined pattern, means for driving said pin feeding means and for shifting said pin setting means in timed relation to supply a pin to each pin retainer and to move the pin setting means step-by-step to align the pin retainers in sequence with the pin delivery station, and valve means operable by rotation of said pin feeding means to deliver a blast of air thereto for ejecting each pin at said delivery station.

4. A machine of the character described comprising a rotary pin cutter adapted to receive a continuous length of wire and to cut the same into pins, rotary pin feeding means for receiving each pin from said pin cutter and transferring it to a delivery station, pin setting means shiftable in two directions to move in a plane adjacent said pin delivery station and having pin retainers to receive and retain pins in a predetermined pattern, a common drive shaft, means operatively connecting said pin cutter with said common drive shaft, means operatively connecting said pin feeding means with said drive shaft, means operatively connecting said pin setting means with said drive shaft, said connecting means being operable to rotate said pin cutter and pin feeding means and to shift said pin setting means in timed relationship to receive each pin from the pin cutter, to transfer each pin to said delivery station and to shift the pin setting means to align the pin retainers in sequence with the delivery station, and air jet means for ejecting each pin at said delivery station, said air jet means including a valve operable

by rotation of said pin feeding means to deliver a blast of air thereto to eject each pin at the delivery station.

5. A machine of the character described comprising a rotary pin cutter adapted to receive a continuous length of wire and to cut the same into pins and deliver each pin at a pin receiving station, rotary pin feeding means provided with radial passages to receive said pins at said pin receiving station, and to transfer each pin by rotation to a pin delivery station, shiftable pin setting means shiftable in two directions to move in a plane adjacent said pin delivery station and having pin retainers to receive and retain pins in a predetermined pattern, and means for driving said pin cutter, said pin feeding means and said pin setting means in timed relationship to supply a pin to each radial passage at said receiving station, to deliver each pin to said delivery station and to shift said pin setting means step-by-step to bring the pin retainers in sequence into alignment with said delivery station.

6. A machine of the character described comprising a rotary pin cutter adapted to receive a continuous length of wire and to cut the same into pins and deliver each pin at a pin receiving station, rotary pin feeding means provided with radial passages to receive said pins at said pin receiving station, and to transfer each pin by rotation to a pin delivery station, shiftable pin setting means shiftable in two directions to move in a plane adjacent said pin delivery station and having pin retainers to receive and retain pins in a predetermined pattern, means for driving said pin cutter, said pin feeding means and said pin setting means in timed relationship to supply a pin to each radial passage at said receiving station, to deliver each pin to said delivery station and to shift said pin setting means step-by-step to bring the pin retainers in sequence into alignment with said delivery station, and air jet means for ejecting each pin from its radial passage, said air jet means including a valve operable by rotation of said pin feeding means to deliver a blast of air to each radial passage when it reaches said delivery station.
